C. W. WINTHER

PUNCHING MACHINE

Filed April 4, 1922

INVENTOR
CHRISTIAN W. WINTHER.
BY
Frank Waterfield
ATTORNEY

UNITED STATES PATENT OFFICE.

CHRISTIAN W. WINTHER, OF FRESNO, CALIFORNIA.

PUNCHING MACHINE.

Application filed April 4, 1922. Serial No. 549,410.

To all whom it may concern:

Be it known that I, CHRISTIAN W. WINTHER, a citizen of the United States, and resident of Fresno, county of Fresno, State of California, have invented certain new and useful Improvements in Punching Machines, of which the following is a specification.

My invention relates primarily to a punching machine for use in punching holes in shims and gaskets such as are used in automobile construction, and the object thereof is to provide a machine of this character having a multiplicity of punches of varying diameters to suit the various sizes of holes desired, and a revolving die plate having holes therein corresponding to the various diameters of the punches.

Another object is to provide in a device of the above character means for quickly and easily interchanging the punches.

Other objects and advantages will appear hereinafter and, while I have described and shown the preferred form of my invention, it will be understood that I do not limit myself to such preferred form, but that various changes and adaptations may be made therein without departing from the spirit of my invention.

In the drawings accompanying and forming a part hereof:

Fig. 1 is a side elevation of my machine in its operative position with parts broken away.

Fig. 2 is a top plan of Fig. 1.

Fig. 3 is a right hand elevation of Fig. 1.

Fig. 4 is a vertical central section of Fig. 1 with parts in elevation.

Fig. 5 is a detail of the punch operating means.

Fig. 6 is a detail view of a portion of my device.

Referring to the drawings, my device comprises a frame 8, provided with outwardly extending ears 9 and 10 by means of which the device may be permanently secured to a bench or table by bolts or otherwise. At the lower forward termination of frame 8 is provided a bearing 11 upon the upper face of which is adjustably mounted a die plate 12, by means of a stud 13, a nut 14 on the lower end of said stud providing means for locking said die plate against rotation. Die plate 12 is provided with a plurality of holes or apertures 15 of varying sizes to suit the punches it is

intended to use, it being understood that holes 15 are all the same distance radially from the center of die plate 12. Extending from frame 8, at a distance from die plate 12, is a vertically extending bearing 16 in which is provided a vertical opening 17, in which opening are slidably mounted the punches 18. It will be noted that the body of punches 18 are all of the same diameter 65 to fit hole 17, and the lower ends are of a diameter suitable to produce the size of hole required. The upper end of frame 8 terminates in a bearing 19 at right angles to bearing 16, in which is revolubly mounted the punch operating handle 20, by means of pintle 21 integral therewith. As best shown in Fig. 5, the inner face of punch operating handle 20 is provided with an eccentric rim 22, which rim is adapted to fit within slits 23 on the upper end of punches 18, so that as handle 20 is rotated on its pivot, punches 18 will be moved upwardly or downwardly according to the direction the handle is rotated. As shown in the drawings, a right hand rotation of the handle will depress the punch, and an opposite rotation will elevate the same. Extending outwardly from one side of frame 8 is a bearing 24 on which is pivotally mounted one end of a stripper 25, the use of which will be obvious. Mounted upon the rear end of frame 8 is a substantially rectangular box 26 adapted to receive therein the extra punches 18. The rear end of pintle 21 projects through bearing 19 a short distance and is provided with an annular recess 27, the inner edge of which lies in the same plane as the rear edge of bearing 19, and pivotally mounted at one end at one side of bearing 19 is a bifurcated locking member 28, the furcations of which are adapted to be mounted within recess 27 to prevent the withdrawal of pintle 21.

In the operation of my device the locking member 28 will be swung on its pivot to release pintle 21, when handle 20 may be removed and the desired punch positioned in bearing 16. Handle 20 will then be replaced with the rim 22 engaging the recess 23 in punch 18. Nut 14 will then be loosened and die plate 12 rotated to bring the hole therein, which corresponds to the diameter of the punch, into alignment with the punch. The handle 20 will then be rotated to move the punch downwardly into engagement with its respective opening.

Nut 14 will then be tightened to hold plate 12 in its adjusted position. The handle 20 will then be rotated to elevate the punch and the shim or gasket will be positioned upon plate 12. The handle 20 will then be rotated to depress the punch and bifurcate the shim or gasket. Stripper 25 will then be brought into alignment with the punch and retained there and handle 20 will be rotated to elevate the punch when the gasket or shim may be removed.

Having described my invention what I claim is:

1. A punching machine comprising a frame adapted to be mounted upon a stationary structure; a horizontally extending, revolute, die plate mounted in said frame and being provided with a plurality of apertures therein; a vertically extending punch mounted in said frame adapted for engagement with any one of said die plate apertures; a recess in the upper end of said punch; a horizontally disposed operating member mounted in said frame above said punch and being provided with an eccentric rim adapted for engagement with the recess in said punch; a handle for rotating said operating member; a stripper pivotally mounted at one end on said frame and being adapted to be brought into engagement with the lower end of said punch to strip the same.
2. A punching machine comprising a frame; a horizontally extending die plate revolutely mounted in said frame and being provided with a plurality of different sized openings therein; means to lock said plate against rotation; a plurality of punches having the cutting ends thereof of a size to fit the openings in said plate, there being one

punch for each of said openings, each of said punches having a recess in the upper end thereof; a horizontally disposed operating member detachably mounted in the upper end of said frame and being provided with an eccentric rim adapted to engage the recess in said punches; a stripper pivotally mounted at one end on said frame and being adapted to have its free end brought into contact with the cutting end of said punches to strip the same; locking means for said operating member to lock the same in its position for use; and a box extending rearwardly from said frame adapted to have mounted therein the punches not being used.

3. A punching machine comprising a frame; a die plate revolutely mounted in said frame and being provided with a plurality of spaced openings therethrough; means to lock said plate against rotation; a punch slidably mounted in said frame at right angles to said die plate adapted for engagement with any of said die plate apertures; a recess in the side of said punch; an operating member mounted in said frame at the end of said punch opposite the die plate having an eccentric rim adapted for engagement with the recess in said punch, whereby the rotation thereof will cause said punch to move towards or away from said die plate; means to rotate said operating member; a stripper pivotally mounted at one end on said frame and being adapted to be brought into engagement with the lower end of said punch to strip the same.

In witness that I claim the foregoing I have hereunto set my hand this 22nd day of March, 1922.

CHRISTIAN W. WINTHERR.
